UNITED STATES PATENT OFFICE.

EDGAR E. GREVE, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

HYDRAULIC ROTARY DRILLING-MACHINE.

1,111,536.

Specification of Letters Patent. Patented Sept. 22, 1914.

Application filed March 19, 1914. Serial No. 825,875.

To all whom it may concern:

Be it known that I, EDGAR E. GREVE, a citizen of the United States, residing at Pittsburgh, in the county of Allegheny and State 5 of Pennsylvania, have invented certain new and useful Improvements in Hydraulic Rotary Drilling-Machines; and I do hereby declare the following to be a full, clear, and exact description of the invention, such as 10 will enable others skilled in the art to which it appertains to make and use the same.

My invention relates to that class of devices used in drilling Artesian wells, commonly termed hydraulic rotary drilling machines, wherewith are employed a sectional 15 drill-stem and a string of tubing interposed between the drill and the drill-stem.

In the case of deep wells it frequently occurs that the drill-string, which is made up 20 of sections of tubing that are added from time to time, will acquire great length and weight, and as the drill string must be detached from the drill-stem and manipulated whenever a section is to be added to or taken 25 therefrom, it becomes important that such provision should be made therefor as will minimize the loss of time and labor of the operator.

The object therefore of my present invention is the production of a rotary drilling machine and its adjuncts of a character 30 which will permit of a ready and effective conversion of the drilling machine into a machine for manipulating the drilling string, when it becomes necessary to add to 35 or remove sections of the drilling string, and will also facilitate its reconversion into a drilling machine with little loss of time and labor, and with no impairment of the 40 strength or efficiency of the drilling machine, as such.

To this end the main feature of my invention involves the combination with a rotary table, of means for imparting the rotary motion of the table to a drill-stem, 45 means for preventing the rotary motion of the table, when desired, slips for supporting a drill-string, and means interposed between the slips and the means for actuating the 50 drill-stem for supporting a drill-string from the rotary table, whereby the slips may be applied to the rotary table without dismantling it or depriving it of its drill actuating elements.

55 There are other, minor, points of inven-

tion, involving features of elemental construction, and particular combinations of coacting elements, all as will hereinafter more fully appear.

In the drawings chosen for the purpose of 60 illustrating my invention, the scope whereof will be pointed out in the claims, Figure 1 is a vertical central section of a rotary drilling machine embodying my invention, showing a portion of a drilling string in elevation. 65 Fig. 2 is a detached view, in elevation, of the rotary-table shown in Fig. 1, the lower portion of the table broken off. Fig. 3 is a top or plan view of the rotary-table shown in Fig. 1, portions of the cover of the table 70 broken away, and one of the slip-posts and slip-levers removed. Fig. 4 is a top or plan view of the rotary-table shown in Fig. 1, the cover and slides having been removed, and a portion of the upper section of the table 75 broken out. Fig. 5 is a vertical sectional view of the rotary-table, taken in the plane of the line 5—5, Fig. 3, looking in the direction of the arrows. Fig. 6 is a plan view of the roller bearings of the rotary-table. Fig. 7 is 80 a view in side elevation of the roller-bearings of the rotary-table. Fig. 8 is a detail plan view of the ends of the slides, and of the slip-blocks, and slips, showing a modification thereof; and Fig. 9 is a view, in elevation, of a lever which may be used to manipulate the slides which carry the slip-blocks.

Like symbols refer to like parts wherever they occur.

I will now proceed to describe my invention more fully so that others skilled in the art to which it appertains may apply the same.

In the drawings, 1 indicates skids or sills 95 for the support of the bed-plate 2 of a rotary table; 3 indicates the rotary-table, and 4 roller bearings interposed between the bed-plate 2 and rotary table 3.

5, 5^a indicate pillow blocks supported on 100 the skids 1, in which is journaled driving shaft 6, having a pinion 7 for imparting rotary motion to the table 3, said shaft having a polygonal portion 6^a adapted to receive a wrench-bar or equivalent means for arresting and preventing the rotation of rotary-table 3, and thus avoiding the use of what are termed the "back-up tongs" in connecting up or separating the sections of a drill-string. Splined on the shaft 6 is a clutch 8, 110

and a loose sprocket wheel 10, whereby power is communicated to the shaft 6 from any suitable source. The general form of bed-plate 2 is annular, or it is provided with 5 a central opening 2^a and surrounding said central opening 2^a is an annular raceway 2^b wherein is a removable race-plate 2^c on which the bearing rollers 4 travel.

In the present instance, the roller-bearing 10 on which the table rests and travels is comprised of a plurality of conical rollers 4 and 4^a, of two different diameters (see Figs. 6 and 7), those marked 4, which are of the greater diameter, being the bearing rollers 15 proper, and those of lesser diameter, marked 4^a, and which are interposed between the larger rollers, being spacing and anti-friction rollers. The shafts 4^b, 4^c of said rollers are journaled in the concentric rings 9 and 20 9^a and are arranged in a common plane.

In the present instance the rotary-table is comprised of two sections A and B, said sections being annular or provided with a central opening for the passage of a drill-25 stem and drill-string.

The lower annular section A is provided on its under surface with a pendant annular flange or skirt 3^a which extends down through the central opening of the bed-30 plate 2, and said flange is provided below the bed-plate with a peripheral collar 11 bolted or otherwise secured to the flange 3^a to restrain the rise or jumping of the rotary table under the thrust of the drive-35 shaft 6 or the vibration of the drill-string. On the under side of said section A of the rotary table 3 and surrounding the pendant flange 3^a is an annular raceway 3^b corresponding with the raceway 2^b of the bed-40 plate and in this raceway, interposed between the bearing rollers 4 and the rotary table, is a removable race-plate 3^c.

On the under surface of a peripheral over-hanging portion of the section A of the rotary-table is an annular rack 12 with which the pinion 7 on driving-shaft 6 meshes, and on the upper surface of section A, at diametrically opposite points, are slotted lugs or projections 13 (see Fig. 4) for the reception 45 of keys 13^a which connect the sections A, B, and there are also radially disposed grooves or channels 14 for the reception of ribs on the under surface of section B.

B indicates the upper annular section of 55 the rotary-table 3 having upon its under surface radially disposed ribs 15 (see Fig.

2) which enter the channels or grooves 14 on the upper surface of section A, and this section is also perforated at diametrically 60 opposite points as at 16 for the passage of the slotted lugs or projections 13 on the upper surface of section A. The upper surface of section B is divided into segmental chambers 17 and 18, by means of radially 65 disposed vertical walls 19 connected by ver-

tical arc-shaped walls 20. The chambers 17, which are closed toward the central opening of section B are provided in their bottoms with slots or apertures 16 for the passage of the slotted projections 13 on lower 70 section A, while the segmental chambers 18, which are open toward the central opening of section B, and which house the slides 22 that engage the drill stem, are provided with radially disposed grooves or channels 75 21 for the reception of guide ribs 23 on the under surface of said slides.

22 indicate slides which have the general form of a truncated wedge, which, when the slides are in their innermost position, results in an extended bearing between the converging sides of the slides and the radially extending side walls of the chambers 18 that insures an effective support for the slides under thrusts and strains. In 80 order to insure a proper movement of the slides to and from each other on a diametrical line of the table, said slides are provided on their under surfaces with guide ribs 23 which extend longitudinally of the slides 90 and which, when the slides 22 are in their proper positions in chambers 18, enter the guide channels 21 in the bottoms of said chambers.

The inner ends of slides 22 are so formed 95 as to engage a drill-stem and impart to the drill-stem and drill-string the rotary movement of the table when said table is rotated in the drilling operation. The skilled builder will, of course, shape the ends of 100 said slides to the cross section of the drill-stem to be used, consequently in the principal figures of the drawing (see Fig. 3) the inner ends have been shown with T-shaped slots 22^a for use with a drill-stem of general 105 circular cross section with radially disposed peripheral ribs, while in the modification shown in Fig. 8 the ends of the slides are shown as having Y-shaped slots 22^b in order that a drill-stem of polygonal or rectangular cross section may be used. 110

As a provision for manipulating the slides 22 when they are to be moved to or from each other, said slides are formed with slots or recesses 22^a (see Fig. 1) crossed by bolts 115 22^b in order to permit the use of a lever L, and in order to provide a fulcrum for the levers 23 which control the slips 24, post-holes 22^c are formed in the slides 22 in line with the lever slots 22^a for the stepping of 120 a fulcrum-post.

In Figs. 1 and 3 of the drawings 25, 25 indicate slip-blocks carried by the inner ends of the slides 22, and interposed between the slides and the slips 24 in order to support 125 the slips from the rotary table. In the modification shown in Fig. 8 of the drawings these slip-blocks are marked 30. On examining Figs. 1 and 3 of the drawings it will be noted that these slip-blocks 25 have 130

- a vertical flat bearing on the vertical flat faces of the ends of the slides 22, are supported thereon by a shoulder or ledge 25^a (see Fig. 1), and are locked to the slides by 5 T-members 25^b or dovetail connections between the slides and the slip-blocks, and further are provided with eye-bolts 25^c to facilitate the withdrawal of the slip-blocks from the slides.
- 10 The inner faces 25^d of the slip-blocks which are also flat and are inclined downward and inward (see Fig. 1) form seats for and afford support to the wedge-shaped slips 24 which cause the wedge-shaped slips 24 to grip or bite on a drill-string S when it is desired to support the drill-string S from the rotary table.
- 15 The slips 24 have the usual semi-circular serrated gripping faces 24^a adapted to engage a tubing, but their rear surfaces are flat (see Fig. 3) and are inclined (see Fig. 1) as indicated at 24^b, or in other words, while the gripping faces of the slips are semicircular as usual, the general form of 25 the slip and its seat in the slip-block is of rectangular cross-section, which construction uniformly distributes the stress of contact between the slips 24 and the slip-blocks 25 and facilitates the withdrawal of the slip 30 from the slip-block. The slips are provided with eye-bolts and rings 24^c for a purpose which will hereinafter appear.
- In order to protect the slides 22 as well as to prevent them from rising under strains, 35 and also to afford a secure footing on the machine for the operator, while manipulating a drill string, I provide an annular cover 26 which may be secured to the rotary table by set screws 26^a, or in other suitable manner. This cover has lever slots 26^b 40 adapted to register with the slide slots 22^a, lugs 26^c, through which pass bolts 26^d which form fulcrums for lever L, and post-holes 26^e adapted to register with the post-holes 45 22^e in slides 22 when the slides are drawn out or back as indicated in Fig. 1 of the drawing. Extending through the cover and into the slides 22 are the fulcrum posts 27 on which are pivoted the slip-levers 23, the 50 inner ends of which pass through the rings 24^e of the eye-bolts of slips 24. To prevent the accidental disconnection of the slips and slip-levers, pins 23^a may be passed through the slip levers 23.
- 55 The construction being substantially such as hereinbefore pointed out, and the bed-plate, roller-bearings and driving mechanism having been assembled in the usual manner, section A of the table is placed in 60 position on the roller bearings 4 with the annular rack 12 in engagement with pinion 7 of the driving shaft 6, and the peripheral ring 11 is secured to the flange 3^a of the section A to prevent the jumping of the rotary table. The section B of the rotary table is
- then superposed on the section A and the parts securely fastened together by passing the keys 13^a through the slots in lugs 13, after which the slides 22 are placed in slide chambers 18, the annular cover 26 is applied 70 and secured in position by the set-screws 26^a, or in other suitable manner.
- The machine is now organized as a rotary drilling machine, in which condition the slides 22 may be moved toward each other 75 by lever L, or manipulated to engage a drill stem and may be secured in proper relation to the drill-stem and to each other by means of pins passed through the pin holes 31 in cover 26 into pin holes 31^a in slides 22.
- The drilling having proceeded in the usual manner, until it becomes necessary to add a section to the drill-string, the existing organization of the machine is then augmented by moving the slides 22 until the 80 holes 26^e in cover 26 register with the holes 22^e in slides 22, whereupon the fulcrum posts 27 carrying the pivoted levers 23 are inserted in the post-holes 22^e, the slip-blocks 25 are by means of the dovetail connections 85 25^b secured to the inner ends of the slides 22, the slips 24 are inserted in the slip-blocks 25, the inner ends of levers 23 are passed through the rings 24^e which are connected to the slips 24, and pins 23^a are inserted in the 90 pin holes of the levers 23 to prevent the slips 24 from becoming accidentally disengaged from the slip-levers 23.
- When the machine is organized as last noted, that is to say with the slips and slip-blocks combined with the slides, the rotation of the table may be prevented by means of a wrench bar one end of which will engage the polygonal portion 6^a of the drive shaft 6 and the other will bear on the skids 1 or other suitable fixed point, or equivalent means of preventing the rotation of the rotary table may be resorted to, and when so organized and the rotary table has been secured against rotation the machine is in 100 condition to be utilized in adding to or removing sections from a drill-stem and drill-string in introducing or removing the drilling-string from the well.
- In adding to or removing a section from 105 the drill-string, the rotation of the table 3 is first arrested and locked against further movement by means of the wrench engaging shaft 6, or otherwise, as hereinbefore noted, the drill-stem is secured to an elevator in 110 the usual manner, and the slides 22 are withdrawn or moved outward to disengage the drill-stem, after which the slip-blocks 25, slip-levers 23, fulcrum posts 27 and slips 24 are added to the first-named elements of the 115 machine in the manner hereinbefore pointed out. These changes in the organization of the rotary-drilling machine can be readily and rapidly made by a skilled operator, and when made, the slips 24 can be manipulated 120 125 130

by the slip-levers 23 to seize the drill-string S and transmit its weight to the rotary-table 3 or to release the drill string and leave it suspended by the usual elevator.

5 If a section is to be added to the drill-string S the drill-string may be slightly lifted by the usual elevator, the slip-levers 23 manipulated to drop the slips 24 into position in the slip-blocks 25 and into engagement with the drill-string S, whereupon when the string S is lowered by the elevator, the slips 24 will be firmly wedged between the drill-string S and the slip-blocks 25, and the weight of the drill-string 10 will be transmitted to and supported from the rotary-table 3. The drill-stem, or that section of the drill-string to which the elevator is attached, is then disconnected from the remainder of the string which latter is 15 suspendingly supported by the table, and a section of tubing may be then removed from or added to that portion of the drill-string supported by the table, accordingly as it is desired to shorten or lengthen the drill- 20 stem.

When the desired number of drill-string sections have been added to or removed from the drill-string, the slips being withdrawn and reapplied for each section so added or 25 removed, the portion of the string carried by the elevator is connected with the portion of the string supported from the rotary-table, the fulcrum-posts 3 and the slip-blocks 25 and slips 24 are removed, and the 30 machine is thus, with a minimum loss in labor and time, reconverted into a rotary drilling machine.

Having thus described my invention, what I claim and desire to secure by Letters Patent is:

1. In a rotary drilling machine, the combination of a rotary table, slides for imparting the movement of the table to a drill-stem, slips detachably connected with the 45 slides, and means detachably connected with the rotary table for moving the slips into and out of operative position.

2. In a rotary drilling machine, the combination of a rotary table, slides for imparting the movement of the rotary table to a drill-stem, means for restraining the movement of the rotary table, slips detachably connected with the slides, and means detachably connected with the rotary table for 50 moving the slips into and out of operative position.

3. In a rotary drilling machine, the combination of a rotary table, slides for imparting the movement of the rotary table to a

drill-stem, slip-blocks detachably connected with the slides, slips for engaging a drill-string, and means detachably connected with the rotary table for moving the slips into and out of operative position.

4. In a rotary drilling machine, the combination of a rotary table, slides for imparting the movement of the rotary table to a drill-stem, slips detachably connected with the slides, levers for moving the slips into and out of operative position, and fulcrum posts for the levers, said posts detachably stepped on the slides.

5. In a rotary drilling machine, the combination of a rotary table having slide chambers, slides for imparting the movement of the rotary table to a drill-stem, slip blocks detachably connected with the slides, slips for engaging a drill-string, levers for moving the slips into and out of operative position, and fulcrum posts for the levers.

6. In a rotary drilling machine, the combination of a rotary table having slide chambers, slides for imparting the movement of the rotary table to a drill-stem, said slides having post-holes, a cover for the slide-chambers, said cover having post-holes, slips detachably connected with the slides, fulcrum posts stepped in the post-holes of the slides, and levers on the fulcrum-posts for moving the slips into and out of operative position.

7. In a rotary drilling machine, the combination of a rotary table, slides for imparting the movement of the rotary table to a drill-stem, slip-blocks detachably connected with the slides, slips detachably connected with the slip-blocks, the contact surfaces of slips and slip-blocks being flat, and means on the rotary table for moving the slips into and out of operative position.

8. In a rotary-drilling machine, the combination of a rotary table, slides for imparting the movement of the table to a drill-stem, slips detachably connected with the slides, means detachably connected with the 105 table for moving the slips into and out of operative position, and a driving shaft and pinion for imparting rotary motion to the table, the driving shaft having a wrench seat for the application of a wrench to restrain the movement of the rotary table.

In testimony whereof I affix my signature, in the presence of two subscribing witnesses.

EDGAR E. GREVE.
